UNITED STATES PATENT OFFICE.

BENJAMIN SLOTE, OF NEW YORK, N. Y.

BELT-BUCKLE ATTACHMENT.

1,382,130.

Specification of Letters Patent. Patented June 21, 1921.

Application filed December 1, 1920. Serial No. 427,552.

To all whom it may concern:

Be it known that I, BENJAMIN SLOTE, a citizen of the United States, residing at New York, in the county of New York and State 5 of New York, have invented new and useful Improvements in Belt-Buckle Attachments, of which the following is a specification.

This invention relates to belt buckles.

More particularly the invention relates to 10 attachments for the securement of the belt to the buckle.

Some of the objects of the present invention are: to combine with an ordinary belt buckle of any type, an attachment to which 15 one end of a belt is connected; to provide an attachment for a buckle with which one end of a belt may be held in securement with relation to the buckle and without the necessity of sewing or stitching; to combine with 20 an ordinary belt buckle, an attachment in virtue of which one end of a belt may be held in securement with relation to the said buckle, and also permitting the ready adjustment of the belt as to length. With these 25 and other objects in view the invention resides in the particular construction and relative arrangement of parts hereinafter more fully described and illustrated in the accompanying drawing, in which:—

30 Figure 1 is a side elevation of the back of an ordinary belt buckle and showing the preferred form of the attachment of the present invention applied thereto.

Fig. 2 is a horizontal sectional view taken 35 on the line 2—2, Fig. 1, but showing the securement of one end of a belt.

Fig. 3 is a view similar to the view shown in Fig. 2, but showing a modified form of attachment.

40 Fig. 4 is a detached perspective view of another modified form of attachment.

Referring more particularly to the drawings for the details of the present invention it will be manifest that, the belt buckle 10 to 45 which the attachment 11 is applied, may be of any of the types in present use and on the market. The buckle 10 consists essentially of a frame 12 which defines sides 13—13 and ends 14—14, and a central part 15 to which 50 a tongue 16 is secured in movable relation.

The preferred form of attachment 11 shown in Figs. 1 and 2, consists of a frame 17 having parts 18—18, parts 19—19 which connect the parts 18—18, and parts 20—20 55 disposed substantially mid-way of the parts 19—19. The parts 20—20 define a space 21

which accommodates the eye 22 of the tongue 16. The parts 18—18 are bent as at 23 so as to throw the parts 19—19 out and away from the frame of the buckle and thus allow the end of a belt to be readily arranged with relation to the attachment 11 in such a manner that due to the relative disposition of certain parts one end of the belt may be held in securement with relation to the 60 buckle. The attachment 11 is applied to the buckle 10 by the use of clips 24. In the securement of the attachment 11 to the buckle 10 each of the clips 24 encircles the part 15 and part 20. The end portions 25 of the 65 clips 24 are disposed in the same plane with the parts 19—19 thus providing an arrangement of parts for setting up impinging action between portions 26 and 27 of a loop 28 formed at one end of a belt 29 as shown 70 in Fig. 2.

From the foregoing it will be manifest that, one end of a belt may be readily secured with relation to a buckle without requiring sewing or stitching of parts of a belt 80 together and at the same time the length of the belt may be varied to be comfortably and effectively useful.

In the form of the attachment shown in 85 Fig. 3, the central parts 30—30 are provided with flanges 31. The purpose of the flanges 31 is to allow the proper space between the frame of the attachment and the frame of the buckle for the portions of the loop at the end of the belt to be secured, and 90 at the same time allows the hereinbefore referred to portion of the clips 24 to be disposed as explained when a type of buckle 32 is used in which the central tongue supporting part 33 is in the same plane with the 95 sides 34 of the buckle 32.

In the form of the attachment shown in Fig. 4, the parts 35—35 thereof are provided with one or more, preferably two projections 36 which engage sides of the buckle 100 and prevent the attachment end having the said projections from moving against the tongue which might cause the belt to bulge and present an unsightly appearance. This form of attachment is also provided with an 105 apertured projection 37 for the attachment of a strap connected to a loop which encircles the secured end of the belt and the free end thereof after the same has been passed through the buckle. 110

What is claimed is:—

1. The combination with a buckle includ-

- ing a pivoted tongue carrying bar, of a frame having an intermediate portion, the frame being wholly concealed by the buckle and disposed at the rear side of the latter, 5 and a bendable-tongue-bar-engaging means co-acting with said intermediate portion to secure the frame to the buckle.
2. A device of the character described comprising a buckle having a tongue bar and 10 a frame carried by the buckle and located at the rear side thereof, tongue bar engaging means on the frame, and spaced fixed bars spaced relatively and respectively located at the opposite sides of said means, the said 15 means and said bars being relatively in different off set positions, the said means and said bars adapted to co-act with each other for the retention of the folded end of a strap therewith.

3. In a belt buckle attachment of the de- 20 sign adapted to detachably secure one end of a belt to a buckle comprising a substantially rectangular frame provided with an intermediate portion and bars disposed in spaced relation at respectively opposite sides 25 of said intermediate portion, said intermediate portion and said bars adapted to receive the folded end of a strap and to hold said end fixedly folded upon itself in said frame, and means extending from said frame 30 and adapted for connection with the tongue bar of a buckle, said means serving to position the frame at the rear side of the buckle, as and for the purpose specified.

In testimony whereof I hereby affix my 35 signature.

BENJAMIN SLOTE.
